FOLDABLE MOP

William H. Richards and William F. Richards,
Rehoboth, Del.

Application April 15, 1952, Serial No. 282,367

2 Claims. (Cl. 15—119)

1

Our invention relates to scrub mops.

A primary object of the invention is to provide a scrub mop embodying a foldable mophead which greatly facilitates squeezing liquid from the absorbent scrubbing element of the mop.

A further object of the invention is to provide a cleaning or scrubbing device having a novel adjustable handle which enables the device to be used for a wide variety of purposes, such as scrubbing floors and windows, and cleaning under low objects such as radiators and the like.

A further object is to provide a cleaning device or mop of the above-mentioned character which has a readily detachable handle, whereby the device may be used either as a long handle mop or as a hand-scrubbing implement.

A further object is to provide a mop assembly having an adjustable handle which may be raised and lowered and also turned with respect to the mophead and releasably locked in the selected adjusted position.

A still further object of the invention is to provide a device of the above-mentioned character which is sturdy and durable, simplified and economical in construction and reliable in operation.

Other objects and advantages of the invention will be apparent during the course of the following description.

In the accompanying drawings forming a part of this application and in which like numerals are employed to designate like parts throughout the same,

Figure 1 is a plan view of a mop or scrubbing device embodying our invention, part broken away.

Figure 2 is a side elevation of the same.

Figure 3 is an end elevation of the mop.

Figure 4 is a central vertical section on line 4—4 of Figure 2.

Figure 5 is a fragmentary rear side elevation of the mop.

Figure 6 is a fragmentary plan view of the same with the adjustable handle assembly removed.

Figure 7 is a plan view of the mop with the handle extending longitudinally of the mophead and arranged in the lowered or horizontal position, and,

Figure 8 is a side elevation of the mop as illustrated in Figure 7 and showing in dotted lines the operation of the foldable mophead for expelling the liquid from the absorbent element of the mop.

In the drawings, where for the purpose of illustration is shown a preferred embodiment of our invention, the numeral 10 designates gen-

2

erally a foldable mophead or body portion which is elongated and rectangular, as shown. The mophead 10 comprises an elongated rectangular block or pad 11, preferably formed of cellulosic sponge material, or the like. The sponge block 11 is preferably of substantial thickness and may be approximately an inch and one-quarter thick, although this thickness may be varied as desired. A pair of separate substantially flat and rigid backing plates 12 and 13 are fixedly secured to the top of the sponge block 11 by means of waterproof cement, or the like, and these backing plates are generally rectangular and cover the major portion of the area of the top of the sponge block 11, as shown. The backing plates 12 and 13 may be provided at their opposite sides with short depending flanges 14, integral therewith and extending downwardly for a short distance over the sides of the sponge block 11. These flanges 14 add rigidity to the backing plates 12 and 13, and further aid in firmly securing the sponge block to the backing plates. The opposite ends of the elongated sponge block 11 preferably project a slight distance beyond the outer ends 15 of the backing plates 12 and 13, to prevent marring or scratching of furniture and the like during the operation of the mop, since the sponge block is soft and pliable.

The inner ends of the backing plates 12 and 13 are spaced apart longitudinally, and hinge knuckles 15 are formed upon the inner ends of the backing plates near the longitudinal sides of the same, and integral therewith. The hinge knuckles 15 project above the top faces of the backing plates 12 and 13, as shown.

An intermediate mounting plate or adapter 16 is arranged above the backing plates 12 and 13 and extends over the space between the inner ends of the backing plates, at the longitudinal center of the mophead 10. The adapter 16 has a relatively narrow central portion 17, provided at its opposite transverse sides with integral depending hinge knuckles 18, which interfit with the pairs of knuckles 15 formed upon the backing plates. The adapter 16 further comprises elongated longitudinal extensions 19 at the opposite sides of the same and formed integral with the central portion 17 and extending longitudinally outwardly of the hinge knuckles 15 for substantial distances, as shown. The outer ends of the extensions 19 are downturned to provide short depending legs or stops 20, integral therewith and adapted to engage the tops of the backing plates 12 to limit the upward movement of the same. Transverse hinge pins 21 are received

by the interfitting knuckles 15 and 18, for hingedly securing the backing plates 12 and 13 to the adapter 16.

The arrangement is such that the mophead 10 is foldable downwardly from the adapter 16 as shown in dotted lines in Figure 8, for compressing and squeezing the sponge block 11 to expel water or the like from the same. The depending stops 20 prevent the backing plates 12 from swinging above the horizontal positions shown in Figures 2 and 8 during the use of the mop.

Our readily detachable and adjustable handle assembly 22 comprises a generally flat rigid base or mounting plate 23, slidably mounted upon the top of the adapter 16 and detachably pivotally connected therewith by an upwardly directed bolt or screw 24, engaging through registering openings 25 and 26, formed centrally within the adapter portion 17 and mounting plate 23, Figure 4. The bolt 24 is provided above the mounting plate 23 with a washer 27 and a winged nut 28 or the like, adjustable for releasably securing the handle assembly 22 in the selected adjusted position relative to the mophead 10.

The handle mounting plate 23 has a rear integral flat extension 29, projecting horizontally beyond the rear side of the mounting plate 23, and the rear end of the extension 29 is downturned to form a short depending flange or stop 30. This flange 30 is adapted to engage either longitudinal edge 31 of the adapter 16, or either end of the same adjacent to the depending stops 20, when the winged nut 28 is loosened sufficiently to permit turning of the mounting plate 23 upon the adapter 16. The arrangement is such that the mounting plate 23 may be turned a full 360 degrees relative to the adapter 16 and releasably locked in any one of four positions, each 90 degrees apart, by means of the engagement of the depending flange 30 with either longitudinal edge 31 or with either end of the adapter 16. The depending flange 30 is long enough to bridge the gap between the longitudinal extensions 19, Figure 6, when the handle assembly 22 is adjusted to extend longitudinally of the mophead 10. When the winged nut 28 is tightened against the mounting plate 23, the same is forced into tight engagement with the top of the adapter 16, and the depending flange 30 then locks the handle assembly 22 against pivotal or turning movement relative to the mophead 10. The handle assembly 22 is therefore pivotally adjustable relative to the mophead 10 so that the handle may extend either transversely or longitudinally of the mophead, from either side or end of the same.

The mounting plate 23 is provided at its forward end with an integral transverse hinge knuckle 32, disposed above the mounting plate and extending for the full width thereof. At its rear end, the mounting plate 23 has a pair of transversely spaced hinge knuckles 33, integral therewith and disposed forwardly of the extension 29 and depending flange 30. A mop handle 34 of any desired length is provided at its lower end with a plate extension or web 35, rigidly secured thereto by screws 36 or the like and this plate extension is provided at its lower end with a hinge knuckle 37, integral therewith and interfitting with the hinge knuckles 33 of the mounting plate 23. A pin 38 is received by the interfitting knuckles 33 and 37, and serves to hingedly secure the lower end of the handle 34 to the handle mounting plate 23.

Means are provided to adjust the angle of the mop handle 34 from substantially vertical to sub-

stantially horizontal positions. Such means comprises a bail 39 of a stiff wire or the like, including upwardly converging sides 41, formed at their upper ends to provide a transverse bar or latch element 42 having eyes or loops 43 at its opposite ends, and integral therewith. The lower ends of the sides 41 are bent to form short inwardly directed extensions 40, pivotally engaging within the ends of the forward knuckle 32, and removable therefrom by merely flexing the sides 41 outwardly. The bar 42 is adapted to selectively engage within transverse slots or notches 44, formed in the forward side of the handle 34 near its lower end. A retractable coil spring 45 surrounds the rear side of the handle 34 and has its opposite ends secured to the eyes 43 of the wire bail 39. The spring 45 serves to releasably secure the bar 42 within the selected one of the notches 44. By raising the wire bail 39 slightly against the force of the spring 45, the bar or latch element 42 may be readily shifted to any one of the notches 44, to thus change the angle of the handle 34 relative to the mophead 10, as desired. The arrangement is such that when the bar 42 engages the uppermost notch 44, the handle 34 is substantially vertical or perpendicular to the mophead 10, and when the bar 42 engages the lowermost notch 44, the handle is substantially horizontal or parallel to the mophead 10, as shown in Figures 7 and 8.

With the above described arrangement for adjusting the angle of the handle 34 through a full 90 degrees, and coupled with the pivotal adjustment of the handle assembly relative to the mophead 10, by means of the winged nut 28, locking flange 30 and associated elements, the mop is well adapted for use in a wide variety of cleaning operations. For example, with the handle 34 fully lowered and substantially horizontal, Figure 8, and the assembly 22 adjusted to extend longitudinally of the mophead 10, the device is very handy for scrubbing under low radiators or other low pieces of furniture or the like. In other angularly adjusted positions of the handle 34, and with the handle assembly 22 extending transversely of the mophead 10, Figures 1 and 3, the mop is obviously capable of a wide variety of cleaning and scrubbing uses, such as scrubbing floors, washing windows or the like. It should also be mentioned that the sponge mop is also ideal for applying liquid wax or the like to floors, linoleum and the like.

Various component parts of the mop may be made from any desired material, although it is preferred to make the various parts such as the backing plates 12 and 13, adapter 16 and mounting plate 23 from sheet metal, such as aluminum or the like. While the pad or block 11 has been described as a cellulosic sponge block, it should also be understood that any other absorbent pliable scrubbing element may be used, such as sponge rubber, sheepskin or the like.

It is to be understood that the form of our invention, herewith shown and described is to be taken as a preferred example of the same, and that various changes in the shape, size and arrangement of parts may be resorted to, without departing from the spirit of the invention or the scope of the subjoined claims.

Having described our invention, we claim:

1. A mop comprising a compressible scrubbing pad, substantially rigid backing plate sections secured to a side of the scrubbing pad and covering a major portion of said side and being provided at corresponding ends with hinge parts, a

substantially rigid adapter arranged above the backing plate sections and having hinge parts interfitting with the hinge parts of the backing plate sections, pins engaging the hinge parts of the adapter and backing plate sections for hingedly connecting the same and allowing the backing plate sections to swing together in generally parallel relation for compressing the scrubbing pad, the adapter engaging the backing plate sections when the same are longitudinally extended to prevent them from swinging in one direction, a mounting plate slidably mounted upon the adapter and having a flange selectively engageable with different sides of the adapter to releasably secure the mounting plate against turning movement relative to the adapter, adjustable bolt means connecting the adapter and mounting plate and permitting disengagement of the flange and different sides of the adapter, a handle hingedly connected with the mounting plate for angular adjustment relative thereto, and adjustable means connected with the handle to releasably lock the same in the selected angularly adjusted position.

2. A mop comprising a compressible scrubbing pad, backing plate sections secured to one side of the scrubbing pad and being provided at corresponding ends with hinge parts, an adapter plate arranged above the backing plate sections and having hinge parts interfitting with the hinge parts of the backing plate sections, pins engaging said hinge parts of the adapter plate and backing plate sections and hingedly connect-

ing the same and allowing the backing plate sections to swing together in generally parallel relation for compressing the scrubbing pad, the adapter plate engaging the backing plate sections when the same are longitudinally extended and preventing them from swinging in one direction, a mounting plate slidably mounted upon the adapter plate and having a flange selectively engageable with different sides of the adapter plate to releasably secure the mounting plate against turning relative to the adapter plate, adjustable bolt means connecting the adapter plate and mounting plate and permitting disengagement of said flange and different sides of the adapter plate, and a handle connected with the mounting plate.

WILLIAM H. RICHARDS.
